UNITED STATES PATENT OFFICE.

CHRISTIAN F. PAUL, JR., OF AUSTIN, TEXAS, ASSIGNOR TO ERNEST NALLE, W. P. ALLEN, AND ED. ROSENGREN, TRUSTEES, ALL OF AUSTIN, TEXAS.

CENTRIFUGAL SEPARATOR.

1,409,763.

Specification of Letters Patent. Patented Mar. 14, 1922.

Application filed June 15, 1921. Serial No. 477,858.

To all whom it may concern:

Be it known that I, CHRISTIAN F. PAUL, Jr., a citizen of the United States of America, residing at Austin, in the county of Travis 5 and State of Texas, have invented certain new and useful Improvements in Centrifugal Separators, of which the following is a full, clear, and exact description.

This invention relates to centrifugal devices for separating liquid mixtures, emulsions, and the like, and its chief object is to provide a simple and efficient apparatus for separating a heavy oil, such as petroleum, from an acid, for example sulfuric, with 10 which the oil has been mixed or emulsified as a clarifying or decolorizing agent, as in the method described in my copending application Serial No. 477,856. It has been found particularly difficult to effect a clean 15 separation in such cases, but the novel features of my present invention enable me to obtain the desired results in a rapid and effective manner.

One form of the invention, designed especially for the purpose referred to, is illustrated in the accompanying drawing, in which the figure shows my improved separator partly in side elevation and partly in vertical central section.

30 In general the separator consists of a revolving head containing a plurality of concentric annular chambers through which the mixture or emulsion flows upwardly and downwardly in alternation, following the vertical inner and outer surfaces or walls 35 of the chambers. In this flow of the mixture the lighter constituents tend to take the inner path and the heavier constituents the outer path, finally emerging in two separate streams.

In the present embodiment the separating head comprises a hollow carrier 10, substantially conical in form, having at its apex a tapered opening fitting tightly the correspondingly tapered upper end of a vertical driving shaft 11 on which the head is removably secured by means of a nut 12. The shaft itself rotates in upper ball bearings 13 carried in the upper end of a hollow conical standard 14 the outwardly flaring lower end of which rests on the top 15 of the chamber 16. At its lower end the shaft is fixed to a cone 17 constituting a friction clutch member. The other member is the 55 conically recessed annulus 18, connected with

a rotary driving device 19, the outer portion of which constitutes a pulley, rotated by a suitable belt, not shown. The part 19 houses an improved supporting and actuating mechanism for the shaft 11, which forms the 60 subject of my copending application Serial No. 477,860. At the axis of the device 19 is a vertically movable stem 20 upon the upper end of which rests a hardened steel plug 21 set in the lower end of the shaft 11. 65 The lower end of the stem is connected to the short arm of a lever 22, fulcrumed at 23 and connected at the end of its longer arm to the lower end of a vertical rod 24 which is threaded at its upper end to receive an 70 axially stationary nut 25 mounted to rotate in a collar 26 on the side of the housing 27. The parts just described are provided for the purpose of starting and bringing up to speed the separating head (in part composed 75 of the carrier 10) which in large units may weight several thousand pounds. When it is desired to start the apparatus the nut 25 is turned to rock the lever 22 counterclockwise, thereby raising the stem 20. This lifts 80 the cone 17 out of the clutch member 18, so that the device 19 can be started and brought up to the desired speed. The nut is then turned back, to lower the stem 20, thus letting the cone 17 gradually into its seat. As 85 the clutch begins to take hold it imparts motion to the shaft 11 and the load carried thereby, at first slowly, then faster and faster as the cone 17 seats itself, until finally 90 the slippage of the clutch ceases and both members rotate together. In this way the apparatus can be started without the strains or other injury that might result from the enormous inertia of its operative parts and 95 the corresponding amount of energy that otherwise would be required to set such parts in motion. By the method described, but little, if any, more energy is needed to start the machine and bring it up to speed than is required to keep it running after the desired speed has been attained.

The rear wall of the chamber 16 may have a horizontally elongated opening over which is fitted a closure 28 (held in any convenient manner, not shown) which is shorter than the opening so as to leave at each end of the latter a vertical slot for the driving belt. One of these slots is shown at 29.

The bottom 30 of the separating bowl or head has a centrally apertured conical ele- 110

vation at its center, fitting down over the carrier 10 and firmly secured to the flange 31 thereof. The cylindrical outer wall 32 is secured inside of the vertical flange 33 at 5 the outer edge of the bottom 30 and at its top supports a cover 34 in the form of a flat cone having at its apex a wide neck 35.

Surrounding the conical carrier 10 and securely fixed thereto is an inlet chamber 36, 10 having discharge openings 37 in its lower portion and having its upper portion constructed to form an inlet pipe 38. Between casings 36 and 32 are four cylindrical casings 39, 40, 41, 42. Casing 41 has a conical bottom 15 fixed to the bottom 30 and at its top is provided with an inwardly extending upwardly inclined flange 43. Casing 39 has a similar flange 44 and has a conical bottom fixed between the lower end of casing 36 and 20 the bottom of casing 41. Casing 40 has a conical top fixed on the innermost casing 36, and at its lower edge has an inwardly and upwardly extending flange 45 spaced above the bottom of casing 41. Casing 42 has a 25 flange 46 at its lower edge and has a conical top 47 secured to the top of the casing 40 and having at its apex a neck 48 snugly embracing the inlet tube or neck 38.

At its top, casing 39 carries a circumferential series of tubes 49, which communicate at their inner ends with the interior of the casing mentioned and at their outer ends are open close to the inner surface of casing 40. Similar discharge tubes 50, 51, 52, are provided at the top of casing 41 and at the bottom of casings 40 and 42, respectively.

Between the covers 34 and 47 is a conical partition 53, having at its apex a neck 53^a, surrounding but spaced from the neck 48. 40 The partition named provides two conical passages, 54, 55, the latter discharging into the neck 53^a which in turn discharges into the flat chamber 56 provided with the lower discharge spout 57. The passage 54 discharges 45 into neck 53^a which in turn delivers its effluent into the chamber 58 equipped with the upper spout 59.

It will of course be understood that the chambers 27, 56 and 58 are stationary. 50 The emulsion or other mixture to be separated is supplied to the pipe 38 at a suitable rate and enters the first annular chamber through the openings 37. Here separation begins, the heavier ingredient seeking the 55 outer wall (39) and escaping through the tubes 49 while the lighter ingredient takes an inner path and escapes over the edge of the flange 44. In the next chamber the heavier ingredient descends along the wall 40 and passes into the next chamber through the tubes 51 while the lighter ingredient descends along the outer surface of wall 39 and escapes under the flange 45. In like manner the ingredients flow through the succeeding 60 chambers, the heavier finally rising along

the inner surface of the wall 32 and entering passage 55 above the separator or partition 53. From this passage the heavier ingredient overflows neck 35 into the chamber 56 and thence passes to the discharge spout 57. At the same time the lighter ingredient rises along the outer surface of wall 42 into passage 54, thence overflowing neck 53^a into chamber 58 and flowing to discharge spout 59.

The size and proportions of the various parts may be varied, but for use in the process described in my copending application Serial No. 477,856, hereinbefore mentioned. I have secured good results with a machine 80 in which the outer revolving wall 32 is about four and a half feet in diameter. A bowl of this size, running at a speed of 3000 R. P. M. or higher, gives a notably clean separation, the discharge from the lower spout 57 being 85 a heavy sludgy or tarry material containing practically all the excess acid, and that from the upper spout being light colored translucent oil having a slightly acid reaction.

I do not claim herein the supporting and 90 driving parts indicated at 17, 18, 19, since these are described in more detail and are claimed in my copending application Serial No. 477,860.

I claim:

1. In a centrifugal separator, in combination, a plurality of concentric cylindrical walls spaced radially apart to form a series of co-axial chambers through all of which a liquid mixture may flow in succession and 100 separate according to the specific gravities of its constituents, said chambers being in communication with each other at top and bottom alternately, means associated with said chambers for permitting the lighter 105 constituent to escape only at points adjacent to the inner wall of each chamber and pass thence into the succeeding chamber and means associated with said chambers for permitting the heavier constituent to escape 110 only at points adjacent to the outer walls of the chambers.

2. In a centrifugal separator, in combination, a pair of co-axial cylindrical shells spaced apart radially to provide an annular 115 separating chamber between them; a plurality of tubes arranged in a circumferential row around and carried by one of the shells, said tubes extending radially outward and adapted to convey liquid from inside the 120 shell and discharge it at points relatively remote from the shell; a similar row of tubes carried by the other shell at the other end thereof; an inwardly extending flange on one of the shells at one end thereof; and an inwardly extending flange at the other end of the other shell.

3. In a centrifugal separator, in combination, a pair of co-axial cylindrical shells spaced apart radially to form an annular 130

chamber between them; a circumferential series of radially extending tubes carried by the inner shell at one end thereof to receive liquid from inside of said inner shell and 5 discharge the same at points adjacent to the outer shell, and a flange at the opposite end of the outer shell, said flange extending radially inward toward the inner shell but leaving an annular space around the latter 10 for the escape of liquid.

4. In a centrifugal separator, in combination, a plurality of concentric cylindrical walls spaced apart radially to form a plurality of co-axial annular separating chambers; inwardly extending flanges at the upper edges of alternate walls, each leaving an annular space between the flange and the next adjacent inner wall; radially extending delivery tubes at the bottom of said alternate 20 walls for conveying liquid from the inner surfaces of such walls and discharging the same at points adjacent to the next outer wall; inwardly extending flanges at the lower edges of the intermediate walls, each 25 leaving an annular space between the flange and the next adjacent inner wall; radially extending delivery tubes at the top of the intermediate walls for conveying liquid from the inner surfaces of such walls and dis- 30 charging the same at points adjacent to the next outer wall; means for conducting away separately the liquid delivered through the last annular space and the liquid delivered by the last tubes; and means for rotating 35 the said separating chambers.

5. In a centrifugal separator, in combination, a plurality of co-axial cylindrical shells spaced radially apart to form concentric annular chambers, closed at the top but open 40 at the bottom; co-axial cylindrical shells between the first-named shells to form concentric annular chambers therebetween; means for conveying heavy liquid from the outer wall of each chamber to the outer wall of the 45 next outer chamber; means permitting light liquid to flow from chamber to chamber along the inner walls thereof; means associated with the last chamber for carrying off the heavy and light liquids separately, 50 and means for rotating said shells.

6. In a centrifugal separator, in combination, a cylindrical shell forming a central receiving chamber of cylindrical form with its axis vertical, and provided with a plurality of outlet openings in its lower portion; a second cylindrical shell outside of and co-axial with the central shell to form a separating chamber between them, said second shell having at its lower edge a flange 55 60 closing the bottom of said chamber and having at its upper edge a flange extending in-

wardly toward the first shell to leave an annular passage around the latter; a circumferential series of radial discharge tubes carried by the second shell near the top thereof 65 below said flange to convey liquid from inside the annular chamber near the outer wall thereof and discharge the liquid at points relatively remote from the said wall; a third shell concentric with the second, having at 70 its top a cover extending over the second shell to the first, and having at its bottom an inwardly extending flange to provide an annular passage around the second shell, the third shell having also a circumferential series 75 of radial discharge tubes to receive liquid inside such shell at the inner surface thereof and discharge the liquid at points relatively remote from the shell; means for carrying away separately the liquids discharged through the last-mentioned annular passage and the liquid discharged through the last mentioned series of tubes; and means for rotating the shells.

7. In a centrifugal separator, in combination, an outer shell of cylindrical form having a closed bottom and an upwardly conical top having a discharge opening at its apex; a cylindrical shell inside of the first, co-axial therewith but spaced radially therefrom, its lower 90 end spaced from the bottom of the first, and having a conical top spaced from the top of the first and provided with a neck extending upwardly through and spaced from the edge of said discharge opening; a conical separator between the tops of the said shells and having at its apex a neck extending upwardly through said discharge opening but spaced from the edge of the latter and from the other neck; a series of concentric cylindrical inner shells inside of the second-mentioned shell, extending from the bottom of the outer shell but having their upper edges spaced from the top of said second shell; a series of inner cylindrical concentric shells extending downwardly from the top of the second shell but having their lower edges spaced from the bottom of the latter; the shells providing a series of concentric separating chambers communicating at top 100 and bottom alternately; means for conducting relatively heavy liquid from the outer wall of one chamber to the outer wall of the next throughout the series; means for conducting relatively light liquid from the inner wall of one chamber to the inner wall of the next throughout the series; and means for rotating the chambers.

In testimony whereof I hereto affix my signature.

CHRISTIAN F. PAUL, JR.
